United States Patent Office.

HIRAM HERRICK, OF BOSTON, MASSACHUSETTS.

Letters Patent No. 62,134, dated February 19, 1867.

PIANO-FORTE ACTION.

The Schedule referred to in these Letters Patent and making part of the same.

TO ALL PERSONS TO WHOM THESE PRESENTS SHALL COME:

Be it known that I, HIRAM HERRICK, of Boston, in the county of Suffolk, and State of Massachusetts, have invented a new and useful Piano-Forte Action; and do hereby declare the same to be fully described in the following specification, and represented in the accompanying drawing, which is a side elevation of it.

The object of my invention is to insure a repeat or rapid repetition of the blow of the hammer of the piano-forte action, and also ease of touch or action of the key of the hammer. To obtain such, the hammer, after each blow, is prevented from suddenly dropping, so as to prevent the fly from entering the notch of the hinge-block of the hammer. This is accomplished by means of an arm extended upward from the key, and connected with the hinge-block by a string. To this arm and the key an adjusting-lever and a regulating-screw and an arresting-button are applied, as hereinafter described, the same being for the purpose of adjusting the arm, and causing to correctly perform its function.

In the drawing, A denotes the key; B, the hammer; and C, the fly or jack of a piano-forte action. The hinge-block *a* of the hammer is connected to an arm, *D*, by means of a silken or other proper cord, *b*, such arm *D* being a curve extended upward from the key *A*, or from a lever, *E*, arranged thereon as represented, such lever being movable in vertical directions on a fulcrum, *c*, going through a block, *d*, fixed on the key. Over the free end of the lever *E* is a padded button, *e*, fixed on the lower end of a regulating-screw, *f*, which is screwed through a stationary rail, *F*. The remainder of the action is as exhibited in the drawing, and is such as is in common use. When the key is struck the arm *D* and its string *b* assist in elevating the hammer; and they so control it in its action as to enable the fly to act with precision in the most rapid movement of the key. The lever *E* is brought against the arresting-button *e* while the key *A* is in movement. By means of the lever *E*, and the regulating-screw and its button, the arm may be adjusted or made to perform its duty to great advantage. With my new or improved piano-forte action rapid "trilling" can be performed with great certainty and to great advantage.

I claim the combination of the arm *D* and its connecting cord *b*, or the equivalent or equivalents thereof, with the piano-forte action, consisting principally of the key *A*, hammer *B*, and jack or fly *C*, as described.

I also claim the combination as well as the arrangement of the lever *E*, and the adjustable stop *e*, or the equivalent thereof, with the arm *D*, and its connection cord *b*, combined with the piano action, as described.
